UNITED STATES PATENT OFFICE.

W. WARRINGTON EVANS, OF WASHINGTON, DISTRICT OF COLUMBIA.

APPARATUS FOR FORMING DENTAL PLATES.

SPECIFICATION forming part of Letters Patent No. 279,365, dated June 12, 1883.

Application filed November 1, 1882. (No model.)

To all whom it may concern:

Be it known that I, W. WARRINGTON EVANS, a citizen of the United States, and residing in the city of Washington, in the District of Columbia, have invented certain new and useful Improvements in Apparatus for Forming Dental Plates, of which the following is a specification.

The invention relates specially to a dental 10 vulcanizer in which the flasks are placed within a chamber or vessel having a surrounding inclosed water and steam space; and my improvements relate to means whereby the said chamber or vessel may be the more perfectly 15 cast or constructed, so as to insure greater safety in its use.

The invention further relates to a construction whereby, in drawing the flasks together, no strain is placed upon the boiler to weaken or 20 have the tendency to fracture it.

Further, the invention relates to the combination, with the boiler, of a safety valve or device for relieving the pressure of steam within the boiler, of means for removing the 25 vapor from the vulcanizing or dry chamber, and of a thermometer or gage.

The invention further relates to details of construction which contribute to the general simplicity, efficiency, and cheapness of the apparatus, as particularly hereinafter explained.

In the accompanying drawings, Figure 1 is a side elevation of the apparatus. Fig. 2 is a vertical section. Fig. 3 is a plan view. Figs. 4, 5, 6, and 7 are details.

Similar letters of reference indicate similar parts in the respective figures.

A is the outside case, made of malleable iron or other metal which is not a ready conductor of heat. It may be constructed as 40 shown—that is, as a hollow shell in the form of a frustum of a cone—or of other suitable shape.

B is a lamp, and a are apertures cut in the sides of the case to insure the necessary admission of air to supply the flame.

C is the boiler, which is made in two cups, b and c, the space d between the two forming a water and steam chamber. The outer cup, b, is provided at its top with an internal thread, b', and the inner cup, c, with a threaded flange, c', by means of which the two cups are united.

By making the boiler in two parts complication in casting is avoided, and both sections may be examined before being fitted together, thereby rendering it certain that sound castings are employed, which aids greatly in insuring safety in the use of the apparatus. The boiler may, however, be made in one casting. The lower part of the space d, or that over the lamp, is contracted in width to decrease the 55 body of water at that point and facilitate the action of the flame on the fluid.

D is the cap, having lugs e, which, on the cap being turned, fit over the inclined planes e' at the top edge of the boiler, securing the cap in 60 place. The cap is provided with annular recesses f, which fit over corresponding projections, f', formed on the top face of the flange e', close joints being obtained by the use of any suitable packing material. The cap has 65 three or more holes in its top, through which pass the bolts g, which are employed in drawing the flasks E together. As shown in Fig. 2, the bolts g are provided with spherical heads g', which rest in washers g'', made of 70 lead or other suitable material, resting within recesses formed in the cap D, the lower ends of the bolts tapping into a plate, h, upon which plate the flasks rest. The under side of the cap is provided with projections i, 75 which rest upon the top of the upper flask. As the bolts g are turned by the use of a wrench on their upper square ends, it will be seen that the plate h is raised or lowered as the bolts are turned to the right or left. As 80 the plate h is drawn up the flasks are crowded against the projections i on the under side of the cap, and no strain whatever is placed upon the boiler. In order to allow for any slight movement of the bolts g at their upper ends, 85 consequent upon irregularities in the flasks, or other cause, the bolt-holes in the flask are enlarged or widened top and bottom, which allows the bolts to move upon their spherical heads g', after the manner of the well-known 90 universal joint formed by a ball and socket. In Fig. 4 a modification of the bolt g and plate h is shown, the lower end of the bolt having a countersunk head fitted in the plate in which it revolves, the upper end of the bolt being 95 threaded and working in the cap D as a nut. The bolt is provided with a conical washer or 100

ring; *j*, which seats upon a lead washer inserted in the cap. A small pin, *k*, may be driven through the top end of the bolt across the conical ring *j*. The center of the cap *D* is perforated for the insertion of a thermometer, *l*, to indicate the temperature of the vulcanizing or dry chamber. A lead washer, *l'*, is inserted at the joint. If desired, the thermometer may be withdrawn and a central plunger for pressing on the top of the upper flask be inserted, or a handle for removing the lid be used.

In Fig. 5 is shown a safety-valve for attachment to the boiler, the boiler being shown in this figure as cast in one piece. A screw-plug, *m*, is tapped into the solid part *c'* at the top of the space *d*. Within the plug is a tension-screw, *m'*, having a longitudinal steam-opening, *m''*. At the inner end of the screw *m* is a spring, *n*, against which bears the back of a conical valve, *n'*, its stem *n''* entering the spring. The conical valve seats in the solid part *c'*, a minute aperture, *o*, leading from its point into the steam-space of the boiler. An overpressure of steam will be relieved through the opening *m''*. As shown in Fig. 6, the safety-valve is applied to a boiler made in two parts.

In order to allow steam or vapor to escape from the dry chamber after the vulcanization has been completed, I provide a small screw-valve, *p*, which, on being turned in the proper direction, opens communication from the dry-chamber to the outer air. Steam may be admitted to the dry or vulcanizing chamber by means of a screw-valve, *q*.

As shown in Fig. 7, a thermometer is screwed into the plug *o'*, which plug is hollow, communicating with the steam-chamber, and may be provided with a spring relief-valve, *t*, having a tension-screw, *t*, by means of which valve an overpressure of steam may be prevented, instead of by the special relief-valve shown in Figs. 5 and 6. If desired, a steam-gage may be substituted for the thermometer.

Water may be admitted to the boiler on unscrewing the packing-nut *r*, into which the thermometer is screwed.

A hinged door, *s*, is placed at the bottom of the casing, and provided with an isinglass panel, *s*, through which the flame may be viewed. The hinged door admits of the ready introduction and removal of the lamp or gas-burner.

The cups forming the boiler may, instead of being cast, be spun or beaten to shape.

The improvements in construction constituting my invention are such as will be readily understood and appreciated by manufacturers and users of this class of apparatuses.

I disclaim in general terms the suspending of the flasks within the boiler, as also the use of a safety-valve as an adjunct to the boiler. I also disclaim the combination of a boiler, a cover having stuffing-boxes, rods, platen, cross-bar, and a central screw, whereby the flasks on the platen may be drawn up against the under side of the cover; but

I claim as my invention—

1. A boiler for a dental vulcanizer, constructed in two separable parts, forming a continuous and surrounding inclosed water and steam chamber, as contradistinguished from a boiler made in one homogeneous body, as set forth.

2. A boiler for a dental vulcanizer, composed of two separable cups united concentrically to form a water and steam space, substantially as set forth.

3. The combination of a boiler, a cap, a supporting plate or platen for the flasks, and screw-bolts for drawing said platen against the cap, whereby no strain is placed upon the boiler, substantially as set forth.

4. A boiler and a platen combined with a cap having reversely-inclined bolt-holes, and suitable packing-washers, and screw-bolts having spherical heads, substantially as set forth.

5. In a dental vulcanizer, a boiler having circumferential inclined planes and annular projections upon its upper face, combined with a cap having securing-lugs and annular depressions upon its under side, substantially as set forth.

6. The combination of a platen, a cap, and a screw-bolt, the latter having a head countersunk in the under side of the platen, and its upper part tapped into the cap, and provided with a conical ring and securing-pin, substantially as set forth.

7. The combination, with a boiler for a dental vulcanizer, of a screw-plug longitudinally perforated, and exteriorly-adjustable tension-screw, helical spring, and conical valve, back-seating against said spring, the apex of the valve seating against a minute aperture leading to the steam-space in the boiler, substantially as set forth.

8. The combination, with the casing of a dental vulcanizer, of a hinged door having a transparent panel, substantially as set forth.

In testimony whereof I have hereunto set my hand and affixed my seal this 26th day of October, 1882.

W. WARRINGTON EVANS. [L. S.]
